JOSEPH E. LAFERRIERE, OF BOSTON, MASSACHUSETTS, ASSIGNOR TO SPRAY ENGINEERING COMPANY, OF BOSTON, MASSACHUSETTS, A CORPORATION OF MAINE.

METAL-CASTING MACHINE.

1,191,085.

Specification of Letters Patent. Patented July 11, 1916.

Application filed March 7, 1916. Serial No. 82,739.

To all whom it may concern:

Be it known that I, JOSEPH E. LAFERRIERE, a citizen of the United States, and a resident of Boston, in the county of Suffolk and State of Massachusetts, have invented an Improvement in Metal-Casting Machines, of which the following description, in connection with the accompanying drawings, is a specification, like characters on the drawings representing like parts.

This invention relates particularly to metal casting machines adapted for use in many different relations. While not limiting myself to such use, I have herein represented my invention as adapted to the manufacture of type and type-bars to which it is peculiarly adapted.

In order that the principle of my invention may be readily understood, I shall describe a single embodiment thereof and illustrate only that form that is adapted to the casting of type-bars, without limiting myself thereto.

In the drawings Figure 1 is a view, partially in side elevation and partially in longitudinal vertical section, of a type-bar casting machine embodying my invention; Fig. 2 is a plan view of the construction shown in Fig. 1; Fig. 3 is a detail in vertical longitudinal section of a portion of the apparatus upon the line 3—3 of Fig. 2 and looking in the direction of the arrows adjacent to said line, the parts being in position to effect the casting of the type-bar; Fig. 4 is a view similar to Fig. 3, but representing the parts separated after the casting action; Fig. 5 is a view mainly in transverse vertical section upon the irregular line 5—5 of Fig. 3 and looking toward the left in said figure; Fig. 6 is a view similar to Fig. 5, but of a modified form of the invention; Fig. 7 is a detail in vertical transverse section upon the line 7—7 of Fig. 6 and looking toward the right in said figure; Fig. 8 is a vertical transverse section upon the line 8—8 of Fig. 6 and looking toward the left in said figure; Fig. 9 is a perspective view of the lower mold member and related parts; Fig. 10 is a front elevation of a still further modified form of one element or feature of the invention and Fig. 11 is a vertical transverse section of a modified form of type-bar that may be cast by the machine herein disclosed.

My invention is particularly adapted for use in the casting of various articles, such,

for example, as plates, ornamental articles and the like. I will in the ensuing description set forth only that form of my invention peculiarly adapted for the casting of type-bars, and shall limit my description thereto without in any wise so limiting the invention.

An important object of that form of my invention adapted to the casting of types and type-bars is to provide a machine for casting that is of simple and comparatively inexpensive construction and that may be manually operated by a single person, and yet may be operated effectively and with sufficient rapidity to permit of its use by printers whose work is not such as to call for the use of a highly organized, expensive, automatic machine such as are now upon the market.

Other objects of the invention will be set forth more fully in and appear from the specification.

In the preferred embodiment of my invention, I provide two mold members having a relative movement toward and from each other. While within the scope of purpose of the invention, either or both members may be made movable, I preferably mount one of said members rigidly with some fixed part of the machine and mount the other member for a to and fro movement with respect thereto. Preferably I provide the melting pot with an extension to which I rigidly secure or with which I may make integral one of said mold members, and I mount the co-acting mold member for up and down reciprocating movement with respect thereto, such movement being in the present embodiment of the invention controlled by a treadle. I also provide a matrix holder or support which in this embodiment of my invention is mounted for movement in a substantially horizontal direction to and from the said mold members, so that the three parts, namely, the two mold members and the matrix holder or support may be brought into close proximity.

Referring more particularly to the drawings, I have in Figs. 1 and 2 represented a frame composed of four uprights 1, 1, 1, 1, which may if desired be formed of tubular metallic material. These uprights are suitably connected by longitudinal and cross members 2, 2, 2, 2 preferably of similar construction and material. Bolted or other-

wise secured to the upper ends of the uprights 1 is a table 3 having two openings 4, 5 therein. The opening 4 is herein represented as circular and therein is mounted 5 the melting pot 6 having preferably integral therewith a flange 7 seated upon the surrounding portion of the table and secured thereto by bolts or screws 8. The melting pot 6 may be of any suitable construction 10 and is herein represented as having integral therewith an inner cylinder-like portion 9 having one or more horizontal inlet openings 10 and also having a suitable plunger 11. The opening or openings 10 are in communication 15 with the surrounding portion of the melting pot, and through them the molten metal enters beneath the piston when the latter is in its elevated position and the said openings are exposed. The cylinder-like 20 portion 9 has laterally and preferably somewhat upwardly extending from its lower end an extension 12 leading to and through the side wall of the melting pot and there communicating with a prolongation 13 25 that is preferably of considerable width and is herein shown as gradually increasing in width to the length of the longest line or bar to be cast by the machine. The extension 13 passes in an upwardly inclined direction 30 through the opening 5 of the table.

The piston 11 may be operated in any suitable manner. I have herein represented it as having pivoted thereto at 14 a link 15 to which is pivoted at 16 an operating lever 35 17, itself pivotally mounted at 18 upon a bracket 19 suitably secured to the upper face of the operating table as by means of screws or bolts 20. I have herein represented the said lever 17 as operating in a vertical plane 40 that is inclined to the longitudinal axis of the table 3, so that the said lever is wholly out of the way of the casting instrumentalities. As is clearly evident from Fig. 2, the forward end of said lever is conveniently located to be grasped by the hand of the operator who stands at the right hand end of the machine, viewing Figs. 1 and 2.

While I may employ any suitable means for maintaining the lead or other metal in 50 the melting pot 6 in a molten condition, I have herein represented a gas pipe 21 located beneath the melting pot and preferably within a surrounding flange or apron 22. The gas or other suitable fuel is supplied by a pipe 23 wherein I have shown a suitable valve 24.

In view of the fact that the machine is primarily intended for hand operation, I have provided the extension 13 of the melting pot which is of such length that the operator is not in close proximity to the melting pot. I have herein shown the melting pot 6 as located at one end of the table 3 and the mold members as positioned near 65 the opposite end thereof, the said extension

13 of the melting pot being of sufficient length to conduct the molten metal to said molding members.

In order to secure the forward end of the melting pot extension 13 to the table, I preferably provide said extension at opposite sides thereof with ears 24' through which pass bolts 24" extending through the table and firmly securing the melting pot extension in place. In order to retain the metal in a molten condition in said extension 13, I may provide any suitable means, but preferably I provide a gas pipe extension 25 controlled by valve 26 and extending in an inclined direction as indicated at 27 beneath and in sufficient proximity to the said extension 13 where it is provided with a suitable number of burner openings 28. Viewing Fig. 2, it will be observed that the said burner pipe extension 27 is centrally located beneath the melting pot extension 13 and that at its extreme forward end it is provided with a transverse member 29 having burner openings 30 therein in sufficient proximity to the extreme forward portion of said melting pot extension 13.

In the disclosed embodiment of my invention as hereinbefore stated, I provide two relatively movable mold members. Preferably and as herein shown I rigidly attach 95 the uppermost mold member 31 to a transverse lip or flange upon the extreme forward end of the melting pot extension 13. This I preferably do by a suitable number of screws 32. I have herein represented the 100 said mold member as substantially L-shaped in cross section, the depending portion thereof being provided with a multiplicity of openings 33, through more or less of which the molten metal will be forced depending 105 upon the position of the lower mold member 34. I have herein represented the said melting pot extension 13 as having a prolonged, downwardly extending flange 35, the upper portion of which is cut away as indicated at 36 to provide a right angle shoulder receiving the lower portion of the upper mold member 31.

The front face 37 of the flange 35 constitutes a guiding surface for the movable mold member 31. In the disclosed embodiment of my invention, the said lower mold member 34 is secured by a suitable number of screws 38 to a block 39 made in two superposed parts if desired, and as represented in 120 Fig. 7, and having two sets of downwardly extending ears 40, 41 for the reception of pins passing therethrough and also through the eyes in the upper ends of a yoke 42. To the said yoke is connected in any suitable 125 manner an upright rod 43 herein shown as tapped into the lower portion of the yoke. The connecting rod 43 may be formed of metal in tubular form and at its lower end is shown as having tapped thereon a head 130.

44 pivotally connected at 45 to a treadle 46, itself pivotally connected at 47 to a bracket 48 secured to and depending from one of the cross members 2 of the frame. When the 5 operator's foot is removed from the treadle 46, the weight of the mold member 34, the connecting rod 43, etc., causes the said mold member to move into position, as shown in Fig. 4, out of molding relation to the upper 10 mold member 31. Preferably I provide the block 39 with a suitable number of dowel pins 49 represented in dotted lines in Fig. 5 and adapted to enter corresponding sockets in the lower mold member 34, thereby insuring 15 the exact positioning of the latter.

I provide a matrix carrier or support which preferably and in this embodiment of my invention is adapted to be manually moved along the table to and from the casting position. For that purpose, I have herein represented the table 3 as having a forward extension 50 provided with a pair of V-shaped grooves 51, 51, wherein rest correspondingly shaped projections upon the under side of 20 the matrix carrier 52, the weight of the carrier being sufficient to retain it in position and permitting it to be readily moved to and fro, and if desired lifted from place. Within the scope of my invention, however, the said 25 matrix carrier may be otherwise guided.

The matrix carrier is provided with an operating handle 53 positioned between outwardly extending ears 54, to which it may be secured by bolts 55 if desired. Upon its 30 front face, the matrix carrier is provided with two wedge shaped ribs 56 with which coöperate suitable means to hold the matrix carrier firmly in position in casting relation to the mold members. While for this purpose I may employ any suitable means, I have herein represented a yoke like frame 57 pivoted at 58 at the opposite sides of the melting pot extension 13. This yoke like frame is preferably provided at its opposite ends with weights 59, 59 to hold it in its inactive position as represented in full lines in Fig. 4 and in dotted lines in Fig. 1. The forward or cross portion 60 of the yoke like frame is herein shown as provided with 35 ribs 61 adapted slidably to engage the wedge like ribs 56 upon the matrix carrier when the latter is in molding position, and thereby securely to hold the several parts in molding relation, as shown most clearly in Fig. 4. For that purpose, I have, as most clearly shown in Figs. 5 and 9, provided a block 75 detachably secured by screws 76 to the mold member 34. Upon the upper face 77 of said block 75, I preferably provide a dowel pin 78 adapted to enter an opening 79 in the upper mold member and thereby to insure correct alignment of the parts. The block 75 is readily detachable, and may be replaced by other blocks of other heights, if it be desired to cast a type-bar of greater or less thickness than that indicated in Fig. 4.

By means of the parts thus far described, a type-bar is cast that is of substantially the entire length of the mold members. I provide means whereby the length of the cast type-bar may be varied. While for this purpose I may provide any suitable means, I have in Fig. 5 represented the upper mold member 31 as having a lateral extension 80 positioned beneath which is a block 81 having a basal flange 82 through which pass set screws 83 tapped into threaded openings 84 in the extension 80 of the upper mold member 31. Between the block 81 and the said extension 80, I position a type-bar length-defining member 85, the inner end of which is adapted to enter between the upper and lower mold members, as clearly shown in Fig. 5. The said member 85 may be slid into any desired position between said mold 110 members, whereby a suitable adjust-

ment in the dimensions of the frame may be secured. The matrix carrier in this form of my invention is represented as consisting of an upright portion 63 and the base portion 64 herein shown as integral with each other. 70 Upon said carrier I position the matrix support proper or stick 65, and I have represented a shim 66 as interposed between the basal portion 67 of the matrix support and the basal portion of the matrix carrier. The 75 matrix support proper 65 is of general L shape in cross section, and I have herein shown dowel pins 68 extending through the parts 64, 66, 67, thereby suitably to position them. As indicated most clearly in Fig. 1, 80 the opposite ends of the matrix support proper 65 has detachably secured thereto by screws 69 and pieces 70, between which the matrices 71 are positioned in assembled relation. The said matrices are securely held 85 in assembled position in any suitable manner, as by means of an adjusting or set screw 72 tapped into an opening in one of the detachable plates 70, as most clearly indicated in Fig. 2.

While in order to define the casting relation of the mold members, I may provide any suitable means, preferably I provide the lower mold member 34 with a detachable block extending above the upper face of the 95 mold member proper to an extent that defines the vertical thickness of the type-bar 73 when the same is in the position shown in Fig. 4. For that purpose, I have, as most clearly shown in Figs. 5 and 9, provided a 100 block 75 detachably secured by screws 76 to the mold member 34. Upon the upper face 77 of said block 75, I preferably provide a dowel pin 78 adapted to enter an opening 79 in the upper mold member and thereby to 105 insure correct alignment of the parts. The block 75 is readily detachable, and may be replaced by other blocks of other heights, if it be desired to cast a type-bar of greater or less thickness than that indicated in 110 Fig. 4.

By means of the parts thus far described, a type-bar is cast that is of substantially the entire length of the mold members. I provide means whereby the length of the cast 115 type-bar may be varied. While for this purpose I may provide any suitable means, I have in Fig. 5 represented the upper mold member 31 as having a lateral extension 80 positioned beneath which is a block 81 having a basal flange 82 through which pass set screws 83 tapped into threaded openings 84 in the extension 80 of the upper mold member 31. Between the block 81 and the said extension 80, I position a type-bar length-defining member 85, the inner end of which is adapted to enter between the upper and lower mold members, as clearly shown in Fig. 5. The said member 85 may be slid 120 into any desired position between said mold members, whereby a suitable adjust-

members, and is then securely held in adjusted position by means of the set screws 83 which clamp the same between said extension 80 and block 81. The inserted end of the type-bar length-defining member covers more or less of the openings 33 in the upper mold member, and hence limits the amount of molten material that is permitted to enter between the mold members.

10 In that form of my invention shown in Fig. 5, the lower mold member 34 is of a single piece extending the entire length of the longest type-bar that may be cast by the machine. If desired, I may form the said member in sections, and in Fig. 6, I have represented another form of my invention wherein I have substituted for said lower mold member 34 a series of blocks 86 each secured to the underlying block 39 by means 15 of screws 87. Preferably also I provide a dowel pin 88 for each block, thus avoiding all possibility of rotative displacement of the block about its screw 87. Viewing Fig. 6, it will be observed that spaces are provided 20 between adjacent blocks 86, thus exposing certain additional molten metal entrance openings 33. The effect of such construction is to form a series of ribs at the rear wall or face of the type-bar. Such 25 ribs are particularly serviceable upon the type-bars having relatively large characters, although they may be used with other forms of type-bars.

In that form of my invention shown in Figs. 6, 7 and 8, I have represented a type-bar length-defining member 89 that is L shaped in cross section, as most clearly shown in Fig. 8. The inner end of said member 89 enters between the upper integral mold member 3, and the series of 30 blocks 86 constituting the lower mold member. The said length-defining member 89 is held in adjusted position by means of adjusting screws 90 passing through a block 45 91 and tapped into the threaded openings 92 in the upper mold member 31.

With that form of my invention shown in Figs. 6, 7 and 8, I cast a type-bar that is L shaped in cross section as indicated at 50 93 in Fig. 11, the type characters 94 being upon the downwardly extending face 95 thereof. The said type-bar is provided with a series of ribs 96 formed between the blocks 86. Except in the respects described, the 55 mold members and related parts shown in Figs. 6, 7 and 8 are substantially the same as those shown in Figs. 3, 4 and 5.

In Fig. 10, I have shown a slightly different form of my invention in that the 60 block 39' of the lower mold member has integral with its upper face a series of projections 93 corresponding in function to the blocks 86. At one end the said block 39 is provided with an upward extension 94 65 corresponding in function to the removable

block 75 in Fig. 9, and the vertical extent of which determines the thickness of the type-bar. The said vertical extension 94 is provided with a dowel pin 95 entering a hole or socket in the upper mold member 31. 70 The type-bar cast by the use of that form of my invention shown in Fig. 10 is the same as that formed by the construction shown in Figs. 6, 7 and 8.

Viewing Figs. 3 and 4, it will be observed that the molten metal is normally maintained at a level just below the lowermost holes 33 in the upper mold member 31, so that a slight elevation of the level 17, as indicated by dotted lines in Fig. 1, will 75 force a sufficient quantity of the molten metal through the exposed openings 33.

I have referred to the lower or movable mold member 34 as guided along the face 37 of the lower flange or extension 34 of the melting pot extension 13. Viewing Figs. 5 and 6, it will be observed that the said surface 37 is provided with a series of vertical grooves 96. These grooves, which may be of any suitable form and number, extend 80 upwardly between the openings 33 in the upper mold member, and their purpose is to permit the escape of air which otherwise might be trapped between the mold members and the matrices in the casting 85 operation. While I may provide other means for the escape of air, I preferably effect it in the manner herein described.

It will be evident from the foregoing description that the machine is of comparatively simple construction and few parts, but that the type-bars may be readily cast with exact predetermined and variable length. Moreover, not only the length but the thickness of the type-bars may be readily 90 varied and different forms of type-bars may be cast by using either that form of my invention shown in Figs. 3, 4 and 5, or that form shown in Figs. 6, 7 and 8. By reason of the fact that the parts are entirely 95 manually controlled and operated, it is evident that the machine may be used by small jobbers expeditiously and economically.

I may employ my invention for work 100 to which the automatically operating machines now on the market are not adapted, as, for instance, in the casting of very large type-bars.

In the foregoing specification, I have set 105 forth in detail various advantages flowing from the use of my invention as a machine for casting type and type-bars. It is, however, clearly to be understood that my invention is not limited to such use, as by 110 suitable variation in the shape of the mold members, I may cast other articles, such, for example, as plates and ornamental objects of various descriptions.

Having thus described one illustrative 115

embodiment of my invention, I desire it to be understood that although specific terms are employed, they are used in a generic and descriptive sense and not for purposes of limitation, the scope of the invention being set forth in the following claims.

Claims:

1. A casting machine comprising in combination, a melting pot having a mold member rigid with the mouth thereof, and a co-operating mold member slideable to and from the first mentioned member and combined from movement in other directions. 10
2. A casting machine having a melting pot provided with a mold member rigid with the mouth thereof, and a co-operating mold member movable in a right line toward and from the first mold member and confined from movement in other directions. 15
3. A casting machine having a melting pot provided with a mold member rigid with the mouth thereof, and a co-operating, manually controlled, mold member slideable toward and from the first mold member and confined from movement in other directions. 20
4. A casting machine having a melting pot provided with a mold member rigid with the mouth thereof, a co-operating mold member, and treadle means for moving the same toward and from the first mold member. 25
5. A casting machine having a melting pot provided with a mold member rigid with the mouth thereof, a slideable, co-operating mold member, and manual means to operate the same. 30
6. A casting machine having a melting pot provided with a mold member rigid with the mouth thereof, a slideable, co-operating mold member, and treadle means to operate the same. 35
7. A metal casting machine comprising in combination, a mold member, a co-operating mold member, means for manually imparting relative movement to said members, and a matrix carrier manually movable toward and from the assembled mold members independently of the said relative movement of said mold members. 40
8. A metal casting machine comprising in combination, a mold member fixed with respect to the body of the machine, a mold member movable to and fro with respect to it, and a matrix carrier movable to and from the fixed mold member in a plane at substantially right angles to that of the movement of the movable mold member. 45
9. A metal casting machine comprising in combination, a mold member fixed with respect to the body of the machine, a mold member movable to and fro with respect to it in a vertical plane, and a matrix carrier movable in a horizontal plane to and from the fixed member. 50
10. A metal casting machine having relatively movable mold members and a matrix carrier manually movable only, in a path to and from said mold members and independent in movement of said mold members. 70
11. A metal casting machine having relatively movable mold members, a supporting table, and a matrix carrier guided for to and fro movement on said table and wholly independent in movement of the movement of said mold members. 75
12. A metal casting machine comprising in combination, a table, mold members supported thereby and a matrix carrier guided for movement along the upper surface of the table toward and from the assembled mold members. 80
13. A metal casting machine comprising in combination, a table, co-operating mold members, the upper one of which is fixed with relation to the table and the lower one of which is vertically movable with respect thereto, and a matrix carrier held in place on said table by its weight and movable 85 thereon. 90
14. A metal casting machine comprising in combination, a table, co-operating mold members, the upper one of which is fixed with relation to the table and the lower one of which is vertically movable with respect thereto, and a matrix carrier held in place by its weight on said table and movable to and fro thereon. 95
15. A metal casting machine comprising in combination, a table, co-operating mold members, the upper one of which is fixed with relation to the table and the lower one of which is vertically movable with respect thereto, and a matrix carrier guided in 100 grooves on the upper surface of said table. 105
16. A metal casting machine comprising in combination, a table, a matrix carrier mounted for sliding movement thereon, an upper mold member fixed with relation to 110 said table and a lower mold member movable vertically to and from the upper fixed mold member. 110
17. A metal casting machine comprising a melting pot having an extension provided with a mold member, and a mold member guided for sliding movement along a face of said extension and confined from movement except along said face. 115
18. A metal casting machine comprising a melting pot having an extension provided with a mold member, and a co-operating mold member guided for vertical movement along a face of said extension and confined from movement except along said face. 120
19. A metal casting machine comprising in combination, a mold member fixed with relation to the body of the machine, a co-operating mold member movable to and from the first, a matrix carrier movable to and from 125 130

and from the assembled mold members, and means to secure the matrix carrier in casting position.

20. A metal casting machine comprising 5 in combination, a mold member fixed with relation to the body of the machine, a co-operating mold member manually movable toward and from the fixed member, a matrix carrier manually movable toward and 10 from the assembled mold members, and means to secure the matrix carrier in casting position.

21. A metal casting machine comprising 15 in combination, a mold member fixed with relation to the body of the machine, a co-operating mold member manually movable in a vertical plane to and from the fixed member, a matrix carrier manually movable in a substantially horizontal plane to and 20 from the assembled mold members, and means to secure the matrix carrier in casting relation to the mold members.

22. A metal casting machine comprising 25 in combination, a melting pot having an extension provided with a fixed mold member, a co-operating mold member, a matrix carrier movable to and from the assembled mold members, and means carried by the melting pot extension to secure the matrix 30 carrier in casting relation to said mold members.

23. A melting casting machine comprising 35 in combination, a melting pot having an extension, a fixed mold member in operative relation thereto, a mold member movable with respect to said fixed member, a matrix carrier movable into casting relation with respect to the assembled mold members, and a yoke to engage the matrix carrier and 40 hold it in casting relation.

24. A metal casting machine comprising 45 in combination, a melting pot having an extension, a fixed mold member in operative relation thereto, a mold member mounted for movement to and from the fixed member, a matrix carrier movable to and from the assembled mold members, and a yoke mounted upon said melting pot extension and adapted to engage the matrix carrier 50 to hold it in casting relation.

25. A casting machine comprising in combination a melting pot having an extension provided with a fixed mold member, a co-operating mold member movable in a vertical path to and from the fixed member, a matrix carrier movable in a horizontal path to and from the assembled mold members, and a yoke pivoted upon said melting pot extension and adapted to engage the matrix 60 carrier and hold it in casting relation to said mold members.

26. A casting machine comprising in combination a melting pot having an overhanging mold member rigid with the mouth thereof, and a co-operating mold member

vertically movable to and from said overhanging mold member.

27. A casting machine comprising in combination a melting pot having an overhanging mold member, means to introduce molten metal laterally beneath said overhanging mold member, and a co-operating mold member vertically movable to and from said overhanging mold member. 70

28. In a type casting machine, a mold 75 member having a dowel-pin receiving socket, and a co-operating mold member having a spacing piece secured to the vertical end face of said co-operating mold member and provided with a dowel-pin to enter said 80 socket.

29. A metal casting machine having a mold member provided with an end extension 85 80 and a block 81 secured thereto, a co-operating mold member and a member positioned at the under side of said extension and between it and said block 81 and slideable longitudinally of said mold members and said extensions and block and adjustable in position to vary the size of the casting product. 90

30. A casting machine comprising in combination a melting pot having an overhanging mold member, means to introduce molten metal laterally beneath said overhanging 95 mold member, and a co-operating mold member vertically movable to and from said overhanging mold member and confined from movement in other directions.

31. A casting machine comprising in combination a melting pot having an overhanging mold member and a guiding extension, means to introduce molten metal laterally beneath said overhanging mold member, and a co-operating mold member vertically movable to and from said overhanging mold member along said extension of said melting pot. 105

32. A type-bar casting machine comprising a mold member provided with an end 110 extension 80, a co-operating mold member, a type-bar length-defining member mounted upon the inner face of the first mentioned mold member and of said extension, and a block 81 and co-operating means 83 to secure 115 said block to said extension 80 to clamp said member in adjusted relation along said mold member.

33. A casting machine having a table, a melting pot having a mold member rigid 120 therewith and positioned over said table, and a co-operating mold member slideable in an upright path through the table toward and from said first mentioned mold member, and confined from movement in other directions. 125

34. A type casting machine comprising in combination, a mold member fixed with relation to the body of the machine, a mold member movable in a vertical path to and 130

- from the fixed mold member and consisting of a single piece of substantially the length of said first mold member, and a matrix carrier manually movable in a horizontal path to and from the assembled mold members.
35. A type casting machine comprising a mold member 31, a melting pot having an extension 13 with which said mold member is rigid, a mold member 34 movable to and from the mold member 31 and having a series of spaced blocks between and over which the molten metal may enter, and means for imparting movement to the movable mold member.
36. A type casting machine comprising in combination, a mold member fixed with relation to the body of the machine, a type-bar length-defining member movable along the under face of said mold member, and a movable, coöperating mold member having a series of spaced blocks between and over which the molten metal may enter.
37. In a type casting machine, a matrix support having upright ends, coöperating means to secure a series of matrices in assembled position upon said support and a machine table upon which said support is mounted for movement into and out of casting relation.
38. In a type casting machine, a matrix support having upright ends, a set screw extending through one of said ends to secure a series of matrices in assembled position upon said support and a machine table upon which said support is mounted for movement into and out of casting relation.
39. In a type casting machine, a table 3, a manually movable matrix carrier 63, 64, having a fixed path of reciprocating movement toward and from the molding means along said table 3, and also a matrix support 65 upon said matrix carrier, and means to secure assembled matrices in position upon said support.
40. In a type casting machine, a manually movable matrix carrier having a fixed path of reciprocating movement toward and from the molding means, a matrix support mounted upon said carrier and having upright ends, and means coöperating with one of said ends to secure an assembled series of matrices in position upon said support.
41. In a type casting machine, a manually movable matrix carrier having a fixed path of reciprocating movement toward and from the molding means, and also having a base and an upright portion, a matrix support similar in form mounted thereon, means for securing said parts in proper relation, and means for securing a series of matrices in assembled relation upon said matrix support.
42. A type casting machine comprising coöperating mold members, a matrix carrier having a handle for manually reciprocating the same toward and from the mold members, and a melting pot having a lever provided with a handle, said handles being located to be conveniently grasped by the same operative.
43. A type casting machine comprising a matrix carrier having a handle for manual manipulation thereof, coöperating mold members, a melting pot having a lever provided with a handle, and a locking member for the matrix carrier also provided with a handle, said handles all being positioned in proximity to each other so as conveniently to be grasped by a single operative.
44. A type casting machine having a fixed mold member, a coöperating mold member movable to and fro along a guiding surface, said surface having formations permitting the escape of air from between the mold members.
45. A type casting machine comprising a melting pot having a prolongation provided with a fixed mold member, a coöperating mold member movable along a guiding surface of said extension, said surface having formations permitting the escape of air from between said mold members.
46. A type casting machine comprising a melting pot having a prolongation, a mold member rigid with said prolongation, and a coöperating mold member vertically slideable along a guiding face of said prolongation, said face being provided with vertical grooves for the escape of air from between said mold members.
47. A metal casting machine, comprising in combination a melting pot, a mold member fixed with relation thereto, a coöperating mold member, means for manually imparting relative movement to said members, and a matrix carrier manually movable toward and from the assembled mold members.
48. A metal casting machine comprising in combination, a mold member, a coöperating mold member, means for manually imparting relative movement to said members in a right line, and a matrix carrier manually movable toward and from the assembled mold members.
49. A metal casting machine, comprising in combination, a melting pot, a mold member rigid with the mouth thereof, a coöperating mold member, means for manually imparting movement to said coöperating mold member toward and from said first mentioned mold member, and a matrix carrier manually movable toward and from the assembled mold members.
50. A metal casting machine, comprising in combination, a melting pot, a mold member rigid with the mouth thereof, a coöperating mold member, means for manually imparting movement to said coöperating mold member toward and from said first mentioned mold member, and a matrix carrier manually movable toward and from the assembled mold members.

mold member toward and from said first mentioned mold member, and a matrix carrier manually movable toward and from the assembled mold members and independent in movement of the movements of said co-operating mold member.

51. A metal casting machine, comprising in combination, a melting pot, a mold member rigid with the mouth thereof, a co-operating mold member, means for manually imparting movement to said co-operating mold member toward and from said first mentioned mold member, and a matrix carrier slidable to and fro in a horizontal path toward and from the mold members and adapted manually to be moved in said path in both directions.

52. A metal casting machine, comprising in combination, a fixed mold member, a mold member movable to and fro with respect to it in a vertical plane, a matrix carrier movable in a horizontal plane to and from the fixed member, and a yoke-like device to engage the matrix carrier and hold it in casting position.

53. A metal casting machine, having a mold member provided with an end extension, a co-operating mold member, and a

member positioned at the under side of said extension and slidable longitudinally of said mold members, and said extension, a block, and means to attach said block to said extension with the slidable member positioned therebetween.

54. In a plate casting machine, a matrix support having upright ends, co-operating means to secure a series of matrices upon said support, said machine having a table along the face of which said support is slidable into and out of casting position.

55. In a type casting machine, a matrix support formed as a relatively heavy block having upright ends, co-operating means to secure a series of matrices upon said support, said machine having a table along the face of which said support is adapted to be manually slid into and out of casting position.

In testimony whereof, I have signed my name to this specification, in the presence of two subscribing witnesses.

JOSEPH E. LAFERRIERE.

Copies of this patent may be obtained for five cents each, by addressing the "Commissioner of Patents, Washington, D. C."

5 mold member toward and from said first mentioned mold member, and a matrix carrier manually movable toward and from the assembled mold members and independent 10 in movement of the movements of said co-operating mold member.

51. A metal casting machine, comprising in combination, a melting pot, a mold member, rigid with the mouth thereof, a co-operating mold member, means for manually imparting movement to said co-operating mold member toward and from said first mentioned mold member, and a matrix carrier 15 slidable to and fro in a horizontal path toward and from the mold members and adapted manually to be moved in said path in both directions.

52. A metal casting machine, comprising in combination, a fixed mold member, a mold member 20 movable to and fro with respect to it in a vertical plane, a matrix carrier movable in a horizontal plane to and from the fixed member, and a yoke-like device to engage the matrix carrier and hold it in casting 25 position.

53. A metal casting machine, having a mold member provided with an end extension, a co-operating mold member, and a

member positioned at the under side of said extension and slidable longitudinally of said 30 mold members, and said extension, a block, and means to attach said block to said extension with the slidable member positioned therebetween.

54. In a plate casting machine, a matrix support having upright ends, co-operating means to secure a series of matrices upon 35 said support, said machine having a table along the face of which said support is slidable into and out of casting position. 40

55. In a type casting machine, a matrix support formed as a relatively heavy block having upright ends, co-operating means to secure a series of matrices upon 45 said support, said machine having a table along the face of which said support is adapted to be manually slid into and out of casting position.

In testimony whereof, I have signed my name to this specification, in the presence 50 of two subscribing witnesses:

Correction in Letters Patent No. 1,191,085.

It is hereby certified that in Letters Patent No. 1,191,085, granted July 11, 1916, upon the application of Joseph E. Laferriere, of Boston, Massachusetts, for an improvement in "Metal-Casting Machines," an error appears in the printed specification requiring correction as follows: Page 5, lines 12-13, claim 1, for the word "combined" read *confined*; and that the said Letters Patent should be read with this correction therein that the same may conform to the record of the case in the Patent Office.

Signed and sealed this 5th day of September, A. D., 1916.

[SEAL.]

Cl. 199—10.

F. W. H. CLAY,
Acting Commissioner of Patents.
